Primary Examiner—Ruth McInroy*Attorney, Agent, or Firm*—Feix & Feix**[57] CLAIM**

The ornamental design for the face guard, as shown.

DESCRIPTION

FIG. 1 is a perspective view, taken from the front, of a face guard showing the design;

FIG. 2 is a front elevation view of the face guard;

FIG. 3 is a left side elevation view of the face guard. The right side elevation view is a mirror image of the view shown in FIG. 3.

FIG. 4 is a top plan view of the face guard;

FIG. 5 is a bottom plan view of the face guard; and,

FIG. 6 is a rear elevational view of the face guard.
